UNITED STATES PATENT OFFICE.

JOSEPH A. OSTROWSKI, OF MILWAUKEE, WISCONSIN.

STRIKING MECHANISM FOR TIME-CLOCKS.

1,361,093.

Specification of Letters Patent. Patented Dec. 7, 1920.

Application filed March 17, 1920. Serial No. 366,552.

To all whom it may concern:

Be it known that I, JOSEPH A. OSTROWSKI, a citizen of Poland, but with declared intention of becoming a citizen of the United States, and a resident of the city of Milwaukee, county of Milwaukee, and State of Wisconsin, have invented a certain new and useful Improvement in Striking Mechanism for Time-Clocks; and I do declare the following to be a full, clear, and exact description thereof, such as will enable persons skilled in the art to which the invention pertains to make and use the same, reference being had to the accompanying drawing for an illustration of one construction in which my invention has been embodied.

The invention relates to striking mechanism for time clocks.

My invention simplifies and materially cheapens the construction of the striking mechanism of a clock, in that I use a single spiral spring as the motive power for the clock, instead of two of such springs, as in modern clock construction. But the invention is applicable also to clocks in which weights are used as the motive power.

I mount the usual striking wheel so as to rotate freely upon the sleeved staff of the hour hand, and connect such wheel to a projection upon the said staff, by means of an auxiliary spiral spring which carries a reserve of initial tension, and which is increased in a slight measure by the rotation of the staff of the hour hand while the striking wheel is maintained in its position of rest between the striking periods.

When the moment for the clock to strike has arrived, the holding detent is released from its engagement with the striking wheel, and the energy stored in the auxiliary spiral spring will set the striking wheel in rotation, the movement of the latter being governed by a vibrating escapement, or a rotating fan, as is usual in striking clocks. The train of mechanism for releasing the holding detent from its engagement with the striking wheel may be of the ordinary construction, and being well known need not be specifically described in the present connection.

The invention also comprises a feature of adjustability, whereby the oscillations of the escapement may be varied so that regulation may be effected in the time of the striking mechanism, rendering such time fast or slow, as may be desired.

In the drawings which form a part of this specification,

Figure 1 is a conventional view of a clock of ordinary construction, the face thereof being broken out so as to show the arrangement of my simplified striking mechanism.

Fig. 2 is a fragmentary view, somewhat enlarged, showing the holding detent as released from its retaining notch in the striking wheel, and as passing over the teeth thereof while the clock is striking.

Fig. 3 is a conventional showing of the devices which control and free for operation the striking wheel.

In the drawings I have shown a clock case and indicated the location of the works therein. One of the plates supporting the works of the clock is indicated by the letter A. The staff for the minute hand is indicated by the letter B, and the sleeved staff for the hour hand by the letter C. Upon the sleeved staff for the hour hand, I mount so as to rotate loosely, a striking wheel D, which is retained in its position of rest between the striking periods by means of a pivoted detent d, the point d' of which is adapted to be seated in the notches d², which latter are cut radially into the periphery of the striking wheel D. The detent d is carried by a pin d³, which is mounted so as to have a rocking movement in the supporting plates of the clock mechanism, and from the said pin extends a stop d⁴ adapted to rest upon the top of one of the plates, and thus limit the entrance of the detent into the notches of the striking wheel.

The detent may be released at the proper time from engagement with the notches of the striking wheel by any of the usual mechanisms employed for that purpose, all of which are well known to clock makers, and need not be further described herein.

The teeth d⁵ on the periphery of the striking wheel are engaged by a pinion d⁶ formed with the escapement wheel d⁷. The escapement E co-operates with the escapement wheel d⁷ to release the striking wheel for retarded movement at the proper time. The sleeve staff C is provided with a radial projection c, and the striking wheel D with a pin c¹, set in one face thereof. An auxiliary spiral spring c² is attached at the inner end of its coil to the radial arm c and at its outer end to the pin c¹. By means of this construction, the escapement wheel will

be made to follow the path of rotation of the sleeved staff C, and inasmuch as the escapement wheel is held against rotation by the detent d, the rotation of the sleeved staff C will put the spring c² under tension, so that when the detent is raised out of its engagement in one of the holding notches in the striking wheel D the latter will have a tendency to rotate, and thus permit the 10 vibrating hammer of the clock to strike the gong. I do not depend upon the energy stored in the spring c², to effect the striking of the clock, but in assembling the parts I put the spring c² under an initial tension 15 by winding such spring in a slight degree. This tension will vary according to the peripheral travel of the striking wheel D, but will be maintained, and will always be sufficient to actuate the striking wheel to 20 effectively strike the maximum number of times desired in the time cycle of the clock.

I have shown the escapement as provided with an extended finger e formed as a light wire along which may be moved a light 25 weight e¹, for the purpose of regulating the fast or slow operation of the escapement and so control the time within which the clock may complete its periodical strike. But instead of the controlling mechanism 30 described, I may employ a rotating fan of usual construction.

While I have shown the striking wheel and its controlling mechanism as arranged at the front side of the clock mechanism, 35 it will be understood that it is not material to the invention that the striking wheel be so arranged but that it may be placed at the rear of the mechanism if desired.

Having thus described my invention, 40 what I claim and desire to secure by Letters Patent of the United States is:

1. In a striking mechanism for clocks, a striking wheel mounted to rotate upon the sleeved staff of the hour hand, a detent to 45 restrain the striking wheel from rotation during the movement of the hour hand, and a spring connection between the said staff and the striking wheel to rotate the latter when the detent is raised.
2. In a striking mechanism for clocks, a striking wheel mounted to rotate loosely upon the sleeved staff of the hour hand, a

detent for restraining the rotation of the striking wheel during the rotation of the sleeved staff, a spring connecting the sleeved staff with the striking wheel to rotate the latter when the detent is raised, and controlling devices for retarding the rotation of the striking wheel. 55

3. In a striking mechanism for clocks, a striking wheel mounted to rotate loosely upon the sleeved staff of the hour hand, a detent for restraining the movement of the striking wheel during the rotation of the sleeved staff, and connections between the 65 sleeved staff and the striking wheel to actuate the latter when released by the detent.

4. In a striking mechanism for clocks, a striking wheel mounted to rotate loosely upon the sleeved staff of the hour hand, a 70 detent for restraining the striking wheel against movement during the rotation of the sleeved staff, connection between the sleeved staff and the striking wheel to rotate the latter when released by the detent, and 75 escapement mechanism for retarding the movement of the striking wheel.

5. In a striking mechanism for clocks, a striking wheel mounted to rotate loosely upon the sleeved staff of the hour hand, a 80 detent for restraining the striking wheel against movement during the rotation of the sleeved staff, connections between the 85 sleeved staff and the striking wheel to rotate the latter when released by the detent, escapement mechanism for retarding the movement of the striking wheel, and adjustable devices for varying the time of the oscillations of the escapement. 90

6. In a striking mechanism for clocks, a striking wheel actuated from the sleeved staff of the hour hand, a detent for restraining the striking wheel from rotation during the movement of the hour hand, and a spring connection between the said staff 95 and the striking wheel to rotate the latter when the detent is raised.

In testimony whereof I have signed my name at Milwaukee this 13th day of March, 1920.

J. A. OSTROWSKI.
